UNITED STATES PATENT OFFICE.

ANDREW WILLIAM ANDERSON, OF CHICAGO, ILLINOIS.

LOCOMOTIVE-SUPERHEATER.

1,010,103.

Specification of Letters Patent. Patented Nov. 28, 1911.

Application filed April 11, 1910. Serial No. 554,800.

To all whom it may concern:

Be it known that I, ANDREW WILLIAM ANDERSON, a citizen of the United States, residing at Chicago, in the county of Cook and State of Illinois, have invented certain new and useful Improvements in Locomotive-Superheaters, of which the following is a specification.

My invention relates in general to locomotive superheaters, and more particularly to superheaters of the smoke tube type for locomotives.

It is desirable that locomotive superheaters should decrease the heating surfaces of the boiler as little as possible, and should not interfere with the cleaning or repair of the boiler flues, while the superheater itself should be composed of parts easily accessible for repair and as free as possible from joints which would be liable to leak. The total cross section in area of the superheater should be as nearly as possible equal to that of the steam supply pipe leading from the throttle valve, so as to permit free passage of steam to the steam chests of the engine cylinders without withdrawing the steam.

The primary object of my invention is to provide a locomotive superheater which will possess the above desirable characteristics, which will be simple in construction, economical in maintenance, and efficient in operation, and which will interfere to a minimum extent with the boiler and smoke-box.

My invention will be more fully described hereinafter with reference to the accompanying drawings, in which the same is illustrated as embodied in convenient and practical form, and in which—

Figure 1 is a central vertical longitudinal section through my improved superheater and the adjacent portions of a locomotive. Fig. 2 is a vertical transverse section through the locomotive smoke-box on line 2 of Fig. 1 showing my improved superheater in position thereon, a portion of the latter being shown in vertical section. Fig. 3 a detail sectional view, taken on the line 3 of Fig. 2. Fig. 4 a horizontal sectional view through the portion of the superheater containing the chambers to which the saturated steam is supplied and from which the superheated steam is delivered. Fig. 5 a plan view of the superheater and adjacent portions of the locomotive, the top of the boiler shell being removed; and Fig. 6 an end ele-

vation of one-half of the boiler header showing the arrangement of flues.

Reference letter A indicates the shell of a locomotive boiler, and B indicates the front flue sheet of the boiler through which extend the fire flues C, while B' indicates the back flue sheet through which extend the opposite ends of the flues.

D indicates the smoke stack, while E indicates the exhaust nozzle leading from the engine cylinder.

F indicates the steam supply conduit leading from the throttle valve.

The above described structure is that of an ordinary locomotive and does not in itself constitute my invention, it being shown in order that the position of my improved superheater may be fully disclosed.

G indicates a metal casing or housing, preferably formed in a casting and provided with an elbow conduit H. This conduit is secured to and communicates with the end of the steam supply conduit F. Any suitable means may be provided for securing a steam-tight union between the elbow conduit H and the steam supply conduit F, such, for instance, as a flange h surrounding the end of the elbow H, which is bolted to a ring f surrounding the conduit F and located inside of the flue sheet B. A gland F' surrounds the end of the conduit F and is clamped between the ring f and flange h, the engaged surfaces of the gland and end of the elbow H being preferably beveled, as shown in Fig. 1, to insure a tight joint.

The casing G is located in the smoke-box of the locomotive at a point slightly above the top row of the boiler flues, and comprises two horizontally elongated chambers K and L, the former communicating with the elbow conduit H and the latter with the steam chests of the engine cylinders, through the medium of the conduit O extending from each end thereof and coupled in any suitable manner around the outlet opening N 100 through the front wall of the chamber L.

Depending from the chambers K and L, and preferably formed integral with the casting G, are a plurality of headers K' and L'. Alternate headers L' communicate with the chamber L, while intermediate headers K' communicate with the chamber K. The headers are shown as nine in number and are spaced apart so as to be staggered with respect to the vertical planes of the series of 110

boiler flues C, as will be clearly seen by reference to Fig. 2. The adjacent headers K' and L' are placed in communication with each other through the medium of a plurality of vertical series of horizontal coils M, which extend within the boiler flues C, each of the vertical series of coils M preferably consisting of four coils, as shown in Figs. 1 and 2. Each of the coils M preferably consists of a tube m, communicating with a header K' and extending through the adjacent boiler flue C toward the rear flue sheet B'. A U-coupling m' is connected to the inner end of the tube m and unites the same with a return tube m² which extends slightly into the smoke-box, where the U-coupling m³ unites the same with a tube m⁴ extending into the same flue C, the inner end of which is in turn united by a U-coupling m⁵ with a forwardly projecting tube m⁶, the latter being connected at its end with the adjacent header L'. The surfaces of the various headers to which the coils are connected are preferably stepped vertically, as shown in Fig. 1, while the front surface of each header is provided with plugs r, closing holes alining horizontally with the ends of the steam coils. The lower coils in each of the several vertical rows extend through flues located in a plane below the bottoms of the headers, as shown in Fig. 1, thereby securing the increased capacity due to four coils in each vertical series, without necessitating the headers being projected downwardly so far as to necessitate the too great lowering of the automatic damper mechanism, which blocks the draft through the boiler flues for preventing the burning out of the coils when steam is not passing through them.

I have shown in Fig. 1 the damper arrangement above referred to, which comprises two horizontally pivoted dampers R' and R², fixed to oscillating rods r' and r², the latter being connected by crank arms united by a link R. An arm S is rigidly secured to the rod r', and is provided with a weight s, which normally operates the dampers to the closed position shown in Fig. 1, thereby cutting off the draft through the flues in which the coils are located. When the throttle valve is open and steam is passing to the cylinders, steam also passes to a motor cylinder U, the piston in which is operatively connected to a crank arm T projecting from the rod r², thereby oscillating the dampers to the open positions shown in dotted lines, so as to permit the flues C in which the coils M are located to be subjected to the draft of the smoke-box. When the throttle valve is closed, and steam thereby cut off from the cylinder U, the weight s falls by gravity and closes the dampers so as to discontinue the draft through the flues in which the steam coils are located. It will of course be

understood that the superheater is protected from the draft, except through the dampers, by means of a partition P, shown in Figs. 1 and 2.

The operation of my improved superheater will be readily understood from the foregoing description. The saturated steam passes from the conduit F, when the throttle valve is open, to the chamber K, thence through the communicating depending headers K' through the vertical series of coils M, back to the intermediate headers L', thence to the chamber L, from which the superheated steam passes through a conduit O, communicating with the ends of the chamber L, to the respective steam chests of the engine cylinders.

It will be observed that the headers, by reason of their locations intermediate the ends of the flues C, do not interfere with the ready access to such flues for the purposes of cleaning or repair. It will be further observed that there is no transverse header or chamber at the lower ends of the headers which would interfere with ready access to the lower row of flues C. It is further evident that by providing vertical series of coils in each of the vertical rows of flues, the capacity of the superheater may be varied without complications or interference with the accessibility of the superheating elements, so as to as nearly as desirable equal the capacity of the steam supply conduit F, hence there is no obstruction to the free passage of steam through the superheater to the cylinder steam chests. Any one of the coils M may be removed when necessary for repairs without disturbing any of the other coils.

My improved superheater reduces to a minimum the danger of leakage, as no gaskets are necessary, the only detachable joints being the usual ones communicating with the conduits O leading to the steam chests and the one communicating with the steam supply pipe F. It is also evident that in my improved superheater all the superheating elements are at all times in direct communication with both cylinder steam chests.

In order to get as high a degree of superheat as possible, I employ the four superheating pipes in each superheating element connected in such a way with return elbows as to cause the steam in passing from the saturated steam chamber to the superheated steam chamber to make two double passages through the small pipes in each large boiler flue, thus insuring as high a degree of superheat as possible before the steam is allowed to pass to the cylinders. In making this kind of a superheating element, I also cut down the number of joints or connections between the superheating pipes and steam header to the smallest possible number. These are the connections

which give the most trouble in present superheaters. As shown in Figs. 1 and 2, I employ a T-header extending the full width of the smoke box and containing a saturated steam chamber and a superheated steam chamber extending the length of the header and located directly above the top row of large superheater boiler flues. These chambers have flat depending chambers located 5 in the central planes extending between the vertical rows of large superheater flues. These depending chambers are connected alternately to the horizontal superheated steam and saturated steam chambers in the 10 main body of the T-header. This T-header, with its depending chambers, is made all of one piece so as to have no steam-tight joints to maintain in the main header and its depending members. As shown in Figs. 15 20 1, 2 and 5, there are but two of the pipes out of the four constituting each superheating element that need to be connected to the adjacent superheated steam and saturated steam depending chambers, and as this is 25 done at the rear side of these chambers by simply expanding the pipes into the depending members, the inside width of these chambers can be limited to the outside diameter of the superheater pipes. In this 30 way the depending chambers can be made so narrow as to leave a channel practically the full width of the large superheating flues and extending the full height of each 35 vertical row of large flues wholly unobstructed, and through these channels every large flue can be gotten at for repairs and for cleaning without disturbing any part of the superheater. By using a small hydraulic jack screwed into the plug openings 40 in the front wall of the depending chambers, the pipes can be jacked out of the adjacent headers simultaneously, and then by simply turning the superheating element an eighth to a quarter of a turn in the large 45 flue to clear the forward ends of the pipes from the depending headers, any superheating element can be removed for repairs and returned without disturbing any of the others. By the use of this expanded pipe connection 50 to the steam headers and only having the necessary bridge metal between adjacent pipes, the depending chamber can be made so short as to leave the lower one or two horizontal rows of superheating flues 55 totally unobstructed, which also leaves the necessary room for a simple and efficient damper construction below the headers. By the use of the flattened steam-pipe, which closely follows the shell of the smoke arch, 60 the top row of large flues can be extended the full width of the boiler and still have the outside flues unobstructed for repairs or removal of the superheating element, by either the header or the steam pipe, which 65 also allows of the full use of the total upper

two thirds of the flue space for the large flues for the superheating coils. This gives a maximum possible amount of superheating area for a given size of boiler.

The construction of my improved superheater is such that sharp bends are eliminated from the connections of the superheating elements with the headers, and in the headers themselves, thereby reducing to a minimum the loss of steam head or pressure 70 and internal losses in the flow of steam. The location of the headers between the front flue sheet and the smoke box partition renders unnecessary baffles between the headers and front flue sheet, thereby simplifying its construction. Another advantage resulting from my improved construction is that all of the coils or flue elements in each horizontal row are the same, thereby reducing the number of differentially bent 75 coils to the number of horizontal rows of coils.

While I have described more or less in detail the embodiment of my improved superheater herein illustrated and described, 90 yet it is to be understood that my invention is capable of embodiment in other specific forms, and may be changed structurally as occasion may require or circumstances may demand, without departing from the spirit 95 thereof.

I claim:

1. In a superheater for locomotives, a wet steam chamber connected to a steam supply, a superheated steam chamber located adjacent to said wet steam chamber, headers depending from said chambers, alternate headers communicating with said first named chamber, and intermediate headers communicating with said second named chamber, 100 said headers being located out of alinement with the boiler flues so as to permit access to the latter, the lower portion of said headers terminating above the level of the lower boiler flues, whereby an increased amount of 105 superheating surface is secured without diminishing the damper space, and superheating coils located in said boiler flues and connecting adjacent headers, the superheating coils in the lowest row of flues being inclined 110 upwardly at their ends, said superheating coils being secured to the rear portion of said headers.

2. In a superheater for locomotives, a wet steam chamber connected to a steam supply, 120 a superheated steam chamber located adjacent to said wet steam chamber, said chambers being located near the top of a locomotive smoke box, headers depending from said chambers, said headers being stepped inwardly and downwardly, alternate headers communicating with said first named chamber and intermediate headers communicating with said second named chamber, said 125 headers being located out of alinement with 130

the boiler flues so as to permit access to the latter, the lower portion of said headers terminating above the level of the lower boiler flues, whereby an increased amount of superheating surface is secured without diminishing the damper space, and superheating coils located in said boiler flues, the superheating coils in the lowest row of flues being inclined upwardly at their ends, said superheating coils connecting adjacent headers and being expanded at their ends in holes in the rear vertical portions of said headers, the front portion of said headers being plugged opposite the connections of said superheating coils with said headers.

3. In a locomotive superheater, a casting located in the smoke box of a locomotive adjacent the top row of boiler flues, said casting comprising a wet steam chamber 20 communicating with a steam supply, a superheated steam chamber communicating with the engine cylinders, and downwardly extending headers, said headers being formed integral with said casting, alternate headers 25 connecting with said wet steam chamber, and intermediate headers communicating with said superheated steam chamber, said headers being located between the vertical rows of boiler flues, whereby access may be had

to the latter, said headers being terminated 30 at their lower ends above the bottom row of boiler flues, and superheating coils communicating with and connecting the rear ends of adjacent headers, said superheating coils being located in the boiler flues.

4. In a superheater for locomotives, a wet steam chamber connected to a steam supply, a superheated steam chamber located adjacent to said wet steam chamber, headers depending from said chambers, alternate headers 40 communicating with said first named chamber and intermediate headers communicating with said second-named chamber, said headers being located out of alinement with the boiler flues so as to permit access 45 to the latter, and a superheating element in each flue comprising a continuous coil of four pipes, the two front ends of the coil being bent laterally immediately outside of the front flue sheet and expanded in openings in the rear surfaces of adjacent headers.

In testimony whereof, I have subscribed my name.

ANDREW WILLIAM ANDERSON.
